WINDING MACHINE

Charles R. Sibley, Marblehead, Mass., assignor to
Sibley-Pym Corporation, Lynn, Mass., a corporation of Massachusetts

Application June 29, 1938, Serial No. 216,535

19 Claims.

(Cl. 242—3)

This invention relates to the manufacture of spherical cores and relates more particularly to the winding of spherical cores with elastic threads or ribbons which are automatically maintained in desired conditions of elongation and tension.

In manufacturing certain types of golf balls, for example, it is desirable to maintain a high degree of tension in the elastic thread which is wound upon the cores. But the higher the degree of tension in the winding thread, the more difficult it is to maintain a uniform tension in the thread, and the more skill and precautions are required on the part of the operator to prevent breakage, all resulting in reduced production and higher manufacturing costs.

This invention provides means for not only elongating the winding thread to provide a desired high degree of tension but also provides means for automatically adjusting the tension to compensate for undesired tension changes and to maintain the desired standard of uniformity. In one embodiment of the invention, the elastic winding thread is advanced first by a relatively slow speed roll and then by a relatively high speed roll to cause the desired degree of elongation and resulting tension in the thread. Another roller in contact with the thread adjacent the core being wound and acting responsive to changes in the tension in the thread at that point, adjusts mechanism which varies the tension of the thread at a remote point to compensate for any changes in tension to maintain the desired uniform tension.

One feature of the invention resides in providing means for regulating the tension throughout a substantial length of the thread for avoiding concentrated strain and resulting danger of breakage. In the embodiment illustrated, the changes in tension adjacent the core control tension adjusting mechanism at the supply reel located a substantial distance from the core.

One object of the invention is to regulate in a novel manner the tension of an elongated, moving, resilient thread or ribbon.

Another object of the invention is to prevent the breakage of moving resilient threads or ribbons which are considerably elongated and so subject to a high degree of tension.

Another object of the invention is to reduce the operative skill and care required for maintaining a uniform high degree of tension in an elongated, moving thread or ribbon.

Other objects of the invention will be apparent from the following description of a preferred

embodiment thereof, selected for purposes of illustration and shown in the accompanying drawings.

Fig. 1 is a front view in perspective of one embodiment of a machine for practicing the invention in the manufacture of golf balls;

Fig. 2 is an enlarged view of apparatus illustrating the arrangement of apparatus included in the embodiment of Fig. 1 but not shown by Fig. 1;

Fig. 3 is a view in front elevation of the elongating rolls of Fig. 1, and

Fig. 4 is a sectional view along the lines 4—4 of Fig. 3.

In the drawings only so much of one embodiment of a machine for practicing the invention, is shown as is needed for a complete understanding of the present invention, and additional details of construction may be found in the U. S. Letters Patent No. 2,033,356 granted March 10, 1936, and No. 2,060,380 granted Nov. 10, 1936 on applications of Arthur F. Pym.

The winding machine illustrated has a main frame which includes the vertical panel 10 from which the rolls 11 and 12 which are arranged side-by-side in horizontal alignment, project. The endless elastic apron 13 extends around the rolls and is adapted to be rotated by one or both of the rolls and to support and rotate the core 20 which is to be wound of the elastic thread 19. One or both of the rolls 11 and 12 may be driven from an external source as shown for example by said Patent No. 2,033,356. The core is maintained in proper position upon the apron 13 by the detector roll 14 which has a curved rim and which is arranged to be rotated freely through contact with the upper side of the rotating core. The detector roll 14 is journaled in the free end of the arm 15 which extends crosswise the front of the panel 10 and is pivotally mounted at its other end on the rotatable shaft 16. As the diameter of the core 20 increases during the winding operation, the arm 15 will move upwardly with partial rotation of the shaft 16. The detector roll 14 also functions to maintain the core spherical in shape by continuously reacting with the last wound turns of the thread to displace the core transversely of the winding plane.

The elastic thread is supplied to the winding machine from the reel 17 which is rotatably mounted in a forked frame 18 which is supported above the panel 10 by the standard 9. The tension of the thread at the reel 17 is adjusted re-

sponsive to changes in tension in the thread adjacent the core 20 as will be explained later.

The thread leaving the reel 17 passes over the grooved guide rolls 20 and 21, both of which are 5 rotatably mounted upon an arm 22 which in turn is rotatably mounted at its center upon the supporting bracket 23 which may be slidably positioned upon the standard 9. The lower end of the arm 22 is attached to one end of the spring 10 24 which is attached at its other end to the supporting arm 25 which in turn is attached to the collar 26 which may be slidably positioned upon the standard 9. The spring 24 acts to exert pressure upon the thread in the grooves of the 15 rolls 20 and 21 to hold it in the grooves by tending to rotate the arm 22 in a counterclockwise direction (facing Fig. 1 of the drawings).

The thread 19 upon leaving the guide roll 21 next passes against the rotatable pressure roll 27 20 and then over the cylindrical tensioning and elongating rolls 28 and 29. The rolls 28 and 29 and their driving gears 30, 31, 32 and 33 are mounted upon the member 34 which is rigidly held on the back side of the panel 10 by the non-rotatable 25 shaft 35. The roll 28 which is the first of the two rolls 28 and 29 with which the thread contacts, is mounted upon one end of the shaft 36 upon the other end of which the gear 30 is mounted. The roll 29 is mounted upon one end of the 30 shaft 37 upon the other end of which the gear 33 is mounted. The gears 31 and 32 are both mounted upon the shaft 38. The shafts 36, 37 and 38 rotate within the bosses 39, 40 and 41 respectively.

35 The pressure roll 27 serves to cause the elastic thread to be wrapped around a substantial portion of the periphery of the roll 28 and another pressure roll 42 rotatably mounted upon the free end of the arm 43 which is pivotally mounted on the panel 10 at 35, serves to cause the elastic 40 thread to be wrapped around a substantial portion of the roll 29. As a result, there is no appreciable slip between the thread and the surfaces of the rolls 28 and 29 with which it contacts.

45 In operation, the roll 28 is rotated by the passage about it of the thread 19. The roll 28 rotates the shaft 36 and through it the gear 30. The gear 30 is meshed with the smaller gear 50 31 and rotates it. The gear 31 rotates the shaft 38 and with it the large gear 32. The gear 32 is meshed with and rotates the small gear 33 which rotates the shaft 37 and with it the roll 29. The gear train steps up the peripheral speed 55 of the roll 29 in a ratio which may for example be 8:1 or greater, with respect to the roll 28. The roll 29 therefore revolves at a much greater speed than the roll 28 and this causes the thread to be elongated to a degree substantially proportional 60 to the ratio of the peripheral speeds of the rolls 28 and 29.

65 The peripheral speed at which the core 20 is rotated by the apron 13 is equal to or slightly in excess of the peripheral speed of the roll 29 with the result that the core is wound with thread which is maintained under the full elongation imparted to it by the rolls 28 and 29 and normally under the full tension required to rotate the roll 70 28 and to drive the gear train connected thereto.

75 The tension of the thread 19 adjacent the core is weighed or measured and continuously balanced to a uniform degree by the action of the dance lever 51 which responds to changes in tension in the thread adjacent the core 20 to adjust

the tension of the thread at the reel 17 to compensate for tension changes.

The dance lever 51 extends cross-wise the front of the panel 10. The roll 50 is rotatably attached to the left hand end (facing Fig. 1 of the drawings) of the dance lever 51 and as illustrated, exerts pressure upon the thread adjacent the core 20. The roll 50 moves upwardly under decreases in tension in the thread, and is moved downwardly upon increases in the tension of the 10 thread. The dance lever 51 is moved correspondingly. The dance lever is attached at its center to the forward end of a shaft 55 journaled in a ball race 52 in the hub member 53 (Fig. 2.) The inner ball race 54 completes the bearing for the 15 shaft 55 and the rear lever 56 is secured to the inner end of the shaft 55 so that the two levers 51 and 56 move together. The lever 56 is attached at one end by the spring 57 to the threaded bolt 58 which is positioned to the upper portion 20 59 of the frame by the thumb nut 60. The other end of the lever 56 is connected by the spring 61 to one end of the upper lever 62. The lever 62 is pivotally mounted at 63 to the back of the panel 10 and contains the central substantially horizontal slot 64.

The slot 64 receives the projection 66 on the rod 65 which extends vertically within the standard 9 which has a central opening freely to receive same. During up and down movement of the 30 lever 62 the projection 66 on the rod 65 rides in the slot 64 without binding, but is confined within the slot to move the rod 65 upwardly and downwardly as the right hand end of the lever 62 (facing Fig. 2 of the drawings) is moved up and 35 down by movement of the lever 56, which movement is caused by movement of the dance lever 51, the movement of which in turn is caused by changes in the tension of the elastic thread adjacent the core.

The upper portion of the rod 65 extends through the arm 66 of the support 67 with the spring 68 tensioned between the arm 66 and the nut 69 which is screwed downwardly upon the threaded upper end of the rod 65 to adjustably tension the 45 spring 68. Supported in the ends of the frame 67 are the rollers 70 with horizontal axis, which rollers rotatably contact with the cylindrical end portions 71 of the reel 17 and which exert variable 50 degrees of pressure upon the reel to variably tension the thread leaving same, in accordance with the up and down movements of the rod 65 caused by the movement of the dance lever 51.

Pivoted supported below the arm 66 on the pivot rod 72 is the member 73 which rests upon the threaded portion of the reel 17. The bolt 74 having a threaded upper portion and a non-threaded lower portion of reduced diameter extends through the arm 66 with its lower end lightly contacting with or closely approaching the upper surface of the member. The spring 71 is coiled around the lower portion 76 of the bolt 74 and is compressed between the upper surface of the member 73 and the lower surface of the arm 66 so that it exerts downward pressure upon the member 73 to cause it to exert downward pressure upon the reel 17. The nut 78 attached to the cylinder 79 through which the bolt extends and which is attached to the arm 79 adjustably positions the bolt upon the arm 66.

The frame 67 has a pair of closely spaced extensions 80 which extend horizontally on both sides of the narrow upright member 81 and fit closely to same. The upright member 81 has its base 82 attached to the frame 18 and serves to 75

prevent side to side movement of the frame 67 during its up and down movement by the rod 65. The rod 83 extends vertically through the arm 66 and is held thereby and its lower end 5 contacts the base 82. The spring 84 is coiled around the rod 83 and is compressed between the base 82 and the arm 66 and exerts upward pressure upon the frame 67 tending to cause it to release its pressure exerted through the rollers 10 and member 73, upon the reel 17.

The lever 85 is pivotally mounted on the front of the panel 10 on the screw 86 which is screwed into the front of the panel. The roller 87 is rotatably mounted in one end of the lever 85 and contacts with the lower surfaces of the rolls 28 and 29. The rod 88 extends through the other end of the lever 85 and is connected at its lower end to one end of the coil spring 89, the other end of the spring 89 being attached at 90 to the panel 10. The effect of the spring 89 is to cause the lever 85 to press the roller 87 against the rolls 28 and 29 to oppose through friction, their movement.

Extending through the right hand ends (facing Fig. 1 of the drawings) of the levers 51 and 85, is the bolt 91 having a threaded upper portion upon which is screwed the nuts 92 for varying the effective length of the bolt and for holding it in position, and having a lower head 93. The bolt 91 is provided for removing the friction of the roller 87 when the machine is started up. When the machine is started up, the end 94 of the dance lever 51 is lifted upwardly by the operator, this causing counterclockwise rotation of the levers 56 and 62 (Fig. 2) and upward movement of the rod 65 to decrease the pressure of the rollers 70 and member 71 upon the reel 17. At the same time, the bolt 91 is lifted upwardly and it lifts the right hand end of the lever 85 upwardly against the influence of the spring 89, and causes the roller 87 to move downwardly out of engagement with the rolls 28 and 29. When the winding has started, the end 94 of the lever 51 is released and the dance lever again controls the tension in the thread at the reel 17, and the roller 87 again contacts the rolls 28 and 29.

When the machine has been started as has just been described, upon release of the end 94 of the dance lever 51, the automatic tensioning mechanism controls the tensioning of and degree of elongation of the elastic winding thread as will now be described.

When increases in tension take place in the thread adjacent the core 20, the roll 50 is moved downwardly causing the dance lever 51 to rotate in a counterclockwise direction and to rotate with it and in the same direction, the lever 56. This causes decreased tension in the spring 61 and reduces the downward pressure of the lever 62 upon the rod 65, permitting the rod 65 to move upwardly under the influence of the spring 84 which exerts pressure upon the frame 67 to move it upwardly from the supporting frame 18. This causes upward movement of the rollers 70 and the member 73 reducing their pressure upon the reel 17 to permit the reel to revolve more freely and thus to decrease the tension in the thread between the reel 17 and the core 20.

When decreases in tension below the desired degree, take place in the thread adjacent the core, the roll 50 moves upwardly causing the dance lever 51 to rotate in a clockwise direction and to rotate with it and in the same direction, the lever 56. This causes increased tension in the spring 61 causing it to pull the lever 62 down-

wardly to cause the rod 65 to move downwardly. This downward movement of the rod 65 causes it to move the frame 67 downwardly to press the rollers 70 and the member 73 more tightly against the reel 17, thus opposing rotation of the reel and 5 causing greater tension in the thread between the reel and the core.

The tension of the thread is thus controlled at the supply reel, the most remotely located point in the machine from the core being wound. 10 The tensioning is thus distributed over a substantial length of thread, thus decreasing the possibility of breakage due to the application of the tensioning force. The tensioning at the supply reel is seen to respond to changes in tension 15 in the thread adjacent the core being wound. Smoothness of action and absence of abrupt action which would tend to break the thread, is provided by the springs 57 and 61 which smooth out the action of the dance lever upon the movement of the rod 65.

Many modifications and changes in detail will readily occur to those skilled in the art without departing from the spirit and scope of my invention and having shown and described an illustrative construction embodying the features thereof, what I claim as new and desire to secure by Letters Patent of the United States is:

1. A golf ball winding machine comprising core rotating means, thread elongating means for supplying elongated thread to said rotating means, means for passing thread from a remote point to said elongating means for elongation, thread tensioning means at said remote point, and means responsive to changes in the tension in the elongated thread between said rotating means and said elongating means for adjusting said tensioning means.

2. A golf ball winding machine comprising a thread supply reel, core rotating means, thread elongating means between said reel and said rotating means, thread tensioning means at said reel, and means responsive to changes in tension in the elongated thread between said elongating means and said rotating means for adjusting said tensioning means.

3. A golf ball winding machine comprising a thread supply reel, core rotating means, thread elongating means between said reel and said rotating means, means for variably impeding the rotation of said reel, and means responsive to changes in tension in the elongated thread between said elongating means and said rotating means for adjusting said means for impeding the rotation of said reel.

4. A golf ball winding machine comprising a panel, core rotating means supported on said panel, thread elongating means supported on said panel, means for passing thread for elongation to said elongating means from a point remote 60 from said panel, a lever pivoted on said panel, a roll rotatably mounted on said lever for contact with the elongated thread between said elongating means and said rotating means, adjustable thread tensioning means at said remote point, and a 65 train of mechanism connecting said lever and said tensioning means whereby movement of said lever is made effective to control the adjustment of the tensioning means.

5. A golf ball winding machine comprising a 70 panel, core rotating means projecting forwardly from the front of said panel, thread elongating means projecting forwardly from the front of said panel, means for passing thread for elongation to said elongating means from a point re- 75

5 mote from said panel, a pivoted lever on the front of said panel, a roll rotatably mounted on said lever for contact with the thread between said elongating means and said rotating means, thread tensioning means at said remote point, and means 10 extending through said panel connecting said lever and said tensioning means for controlling the action of the latter.

6. A golf ball winding machine comprising a 10 panel, core rotating means projecting forwardly from the front of said panel, thread elongating means projecting forwardly from the front of said panel, means for passing thread for elongation to said elongating means from a point remote from said panel, a pivoted lever on the front of said panel, a roll rotatably mounted on said lever for contact with the thread between said elongating means and said rotating means, thread tensioning means at said remote point, a 15 lever pivoted on the back side of said panel, means connecting said levers through said panel, and means connecting said second lever and said tensioning means for controlling the action of the latter.

7. A golf ball winding machine comprising a 20 panel, core rotating means projecting forwardly from the front of said panel, thread elongating means projecting forwardly from the front of said panel, means for passing thread for elongation to said elongating means from a point remote from said panel, a pivoted lever on the front of said panel, a roll rotatably mounted on said lever for contact with the thread between said elongating means and said rotating means, 25 thread tensioning means at said remote point, a lever pivoted on the back side of said panel, means movably connecting said levers through said panel, and means including resilient means and non-resilient means connecting the latter lever and said tensioning means for controlling the action of the tensioning means.

8. A golf ball winding machine comprising a panel, core rotating means supported on said panel, thread elongating means supported on 30 said panel, a thread supply reel supported above said panel, thread tensioning means at said reel, a lever pivoted on said panel, a roll rotatably mounted on said lever for contact with the elongated thread between said elongating means and said rotating means, and means including resilient and non-resilient means connecting said lever and said tensioning means for controlling the action of the latter.

9. A golf ball winding machine having a frame 35 and a panel on the frame, and including in its structure core rotating means projecting forwardly from the front of said panel, thread elongating means projecting forwardly from the front of said panel, a vertical, tubular standard extending upwardly from said frame, a thread supply reel mounted on said standard, means for variably impeding the rotation of said reel, a lever pivoted on the front of said panel, a roll carried by said lever for contact with the elongated thread between said elongating means and said rotating means, and a rod within said standard and having connections at its lower end with said lever and connected at its upper end to said means for impeding the rotation of said 40 reel.

10. A golf ball winding machine having a frame 45 and a panel on the frame, comprising core rotating means projecting forwardly from the front of said panel, thread elongating means projecting forwardly from the front of said panel, a vertical

tubular standard extending upwardly from said frame, a thread supply reel mounted on said standard, means for variably impeding the rotation of said reel, a lever pivoted on the front of said panel, a roll carried by said lever for contact with the elongated thread between said elongating means and said rotating means, a rod connected to said means for impeding the rotation of said reel and extending through said standard to a point behind said panel, and means 50 for connecting said lever behind the panel and said rod for controlling the action of said impeding means on the reel.

11. A golf ball winding machine having a frame and a panel on the frame, comprising core 55 rotating means projecting forwardly from the front of said panel, thread elongating means projecting forwardly from the front of said panel, a vertical tubular standard extending upwardly from said frame, a thread supply reel mounted on said standard, means for variably impeding the rotation of said reel, a lever pivoted on the front of said panel, a roll carried by said lever for contact with the elongated thread between said elongating means and said rotating means, a rod connected to said means for impeding the rotation of said reel and extending through said standard to a point behind said panel, a lever pivoted on the back side of said panel and connected to said rod, and means extending through 60 said panel and connecting said levers whereby one is moved by the other.

12. A golf ball winding machine having a frame and a panel on the frame, comprising core rotating means projecting forwardly from the front of said panel, thread elongating means projecting forwardly from the front of said panel, a vertical tubular standard extending upwardly from said frame, a thread supply reel mounted on said standard, means for variably impeding 65 the rotation of said reel, a lever pivoted on the front of said panel, a roll rotatably mounted upon said lever for contact with the elongated thread between said elongating means and said rotating means, a rod connected to said means for impeding the rotation of said reel and extending through said standard to a point behind said panel, a lever pivoted on the back side of said panel and connected through said panel with 70 said first mentioned lever, and means including resilient means connecting said rod and said lever behind the panel.

13. A golf ball winding machine having a frame and a panel on the frame, comprising core rotating means projecting forwardly from the front of said panel, thread elongating means projecting forwardly from the front of said panel, a vertical tubular standard extending upwardly from said frame, a thread supply reel mounted on said standard, means for variably impeding 75 the rotation of said reel, a lever pivoted on the front of said panel, a roll rotatably mounted upon said lever for contact with the elongated thread between said elongating means and said rotating means, a rod connected to said means for impeding the rotation of said reel and extending through said standard to a point behind said panel, a lever pivoted on the back side of said panel and connected through said panel with said first mentioned lever, a second lever pivoted 80 on the back side of said panel and connected to said rod, and means resiliently connecting the levers behind the panel whereby one moves the other.

14. A golf ball winding machine having a frame 85

- and a panel on the frame, including in its structure core rotating means projecting forwardly from the front of said panel, thread elongating means projecting forwardly from the front of said panel, a vertical tubular standard extending upwardly from said frame, a thread supply reel mounted on said standard, means for variably impeding the rotation of said reel, a lever pivoted on the front of said panel, a roll rotatably mounted upon said lever for contact with the elongated thread between said elongating means and said rotating means, a rod connected to said means for impeding the rotation of said reel and extending through said standard to a point behind said panel, a lever pivoted on the back side of said panel and connected through said panel with said first mentioned lever, resilient means connecting said rod and said lever behind the panel, and means resiliently connecting one of the levers behind the panel and said frame.

15. A golf ball winding machine having a frame and a panel on the frame, comprising core rotating means projecting forwardly from the front of said panel, thread elongating means projecting forwardly from the front of said panel, a vertical tubular standard extending upwardly from said frame, a thread supply reel mounted on said standard, means for variably impeding the rotation of said reel, a lever pivoted on the front of said panel, a roll rotatably mounted upon said lever for contact with the elongated thread between said elongating means and said rotating means, a rod connected to said means for impeding the rotation of said reel and extending through said standard to a point behind said panel, a lever pivoted on the back side of said panel and connected through said panel with said first mentioned lever, a second lever pivoted on the back side of said panel and connected to said rod, means resiliently connecting the two levers behind the panel, and means resiliently connecting one of said latter levers to said frame.

20. A golf ball winding machine having a frame and a panel on the frame, comprising core rotating means projecting forwardly from the front of said panel, thread elongating means projecting forwardly from the front of said panel, a vertical tubular standard extending upwardly from said frame, a thread supply reel mounted on said standard, means for variably impeding the rotation of said reel, a lever pivoted on the front of said panel, a roll rotatably mounted upon said lever for contact with the elongated thread between said elongating means and said rotating means, a rod connected to said means for impeding the rotation of said reel and extending through said standard to a point behind said panel, a lever pivoted on the back side of said panel and connected through said panel with said first mentioned lever, a second lever pivoted on the back side of said panel, said lever containing a slot, a projection on said rod extending in said slot, and means resiliently connecting the two levers which are located behind the panel.

25. A golf ball winding machine having a frame and a panel on the frame, comprising core rotating means projecting forwardly from the front of said panel, thread elongating means projecting forwardly from the front of said panel, a vertical tubular standard extending upwardly from said frame, a thread supply reel mounted on said standard, means for variably impeding the rotation of said reel, a lever pivoted on the front of said panel, a roll carried by said lever for contact with the elongated thread between said elongating means and said rotating means, a rod connected to said means for impeding the rotation of said reel and extending through said standard to a point behind said panel, a lever pivoted on the back side of said panel and connected through said panel with said first mentioned lever, a lever pivoted on the back side of said panel, said lever containing a slot, a projection on said rod extending in said slot, and means resiliently connecting the two levers which are located behind the panel.

30. A golf ball winding machine having a frame and a panel on the frame, comprising core rotating means projecting forwardly from the front of said panel, thread elongating means projecting forwardly from the front of said panel, a vertical tubular standard extending upwardly from said frame, a thread supply reel mounted on said standard, means for variably impeding the rotation of said reel, a lever pivoted on the front of said panel, a roll rotatably mounted upon said lever for contact with the elongated thread between said elongating means and said rotating means, a rod connected to said means for impeding the rotation of said reel and extending through said standard to a point behind said panel, a lever pivoted on the back side of said panel and connected through said panel with said first mentioned lever, a second lever pivoted on the back side of said panel and connected to said rod, means resiliently connecting the two levers behind the panel, and means resiliently connecting one of said latter levers to said frame.

35. A golf ball winding machine having a frame and a panel on the frame, comprising core rotating means projecting forwardly from the front of said panel, thread elongating means projecting forwardly from the front of said panel, a vertical tubular standard extending upwardly from said frame, a thread supply reel mounted on said standard, means for variably impeding the rotation of said reel, a lever pivoted on the front of said panel, a roll carried by said lever for contact with the elongated thread between said elongating means and said rotating means, a rod connected to said means for impeding the rotation of said reel and extending through said standard to a point behind said panel, a lever pivoted on the back side of said panel and connected through said panel with said first mentioned lever, a second lever pivoted on the back side of said panel, said second lever containing a slot, a projection on said rod extending in said slot, means resiliently connecting the levers which are located behind the panel, and means resiliently connecting one of them and said frame.

40. A golf ball winding machine comprising, core-rotating means, a thread supply reel having a retarding device associated therewith, thread-elongating rolls located between said reel and said core-rotating means and having also a retarding device associated therewith, and means under the control of the operator for temporarily and simultaneously releasing both of said retarding devices.

45. CHARLES R. SIBLEY.

CHARLES R. SIBLEY
